SPAGHETTI WRAPPING MACHINE

Matthew Klimas, Richmond Hill, N. Y., assignor
to A. Zerega's Sons, Inc., a corporation of New
York

Application January 8, 1948, Serial No. 1,105

3 Claims. (Cl. 53—111)

1

The present invention relates to the packaging of spaghetti and more particularly to a machine for wrapping spaghetti in cellophane or waxed paper.

Spaghetti and similar products have customarily been marketed in cardboard boxes lined with waxed paper and, to some extent, in bulk and in other forms. There has been for a number of years an increasing tendency to market food products in transparent wrappers not only to expose the contents to view but because such packages have a considerable visual appeal. Many items of food are now marketed in cellophane or waxed paper wrappers. There are machines available for wrapping bread, cake and other food products in cellophane or waxed paper, but these machines are so constructed and operated that the wrapper is rather loosely applied. Such machines cannot, for example, wrap food products with a tightly fitting outer wrapper but such a loose wrapping is not suitable or desirable for spaghetti and similar products, as is well recognized by those familiar with the packaging of this product. A loosely wrapped package of spaghetti would permit undue breakage of the sticks of spaghetti and would permit substantial misalignment of the parallel piled spaghetti sticks. A loosely wrapped package of spaghetti also permits the ends of the sticks to break through the wrapper, thus destroying the marketability thereof and also rendering the same unsightly and insanitary. Consequently, so far as I am aware, it has not heretofore been possible to produce a tightly-wrapped package of spaghetti on any existing machine despite the fact that such is highly desirable.

It is, accordingly, one of the objects of this invention to provide for the first time a machine which is capable of forming tightly wrapped packages of spaghetti in which the outer wrapper is composed of transparent material, such as cellophane or waxed paper.

It is another object of this invention to modify existing loose-wrap machines employed for the wrapping of bread and cake in such manner that a tight outer wrapper of cellophane or waxed paper can be applied to spaghetti to produce a highly attractive, marketable package.

A further object of the invention resides in a machine for producing a tightly wrapped package of spaghetti, the outer wrapper of which is composed of cellophane or waxed paper so applied that it maintains the parallel piled sticks of spaghetti in substantially immovable condition.

2

A still further object of the invention comprises a spaghetti wrapping machine constructed to apply an outer wrapped snugly around a bundle of spaghetti and to fold and seal the ends of the wrapper during the wrapping operation.

Other and still further objects and advantages reside in the various mechanical combinations, sub-combinations and details hereinafter described and claimed and in such other and further matters as will be understood or appreciated by those skilled in this art.

In the accompanying drawings wherein I have illustrated a preferred embodiment of my invention:

15 Fig. 1 is a plan view of a portion of a standard cake wrapping machine to which my invention has been applied;

Fig. 2 is a longitudinal, vertical sectional view taken along line 2—2 of Fig. 1;

20 Fig. 3 is a view similar to Fig. 2 but with the parts in a different condition of operation;

Fig. 4 is a sectional view, partly in elevation, taken along line 4—4 of Fig. 2;

25 Fig. 5 is a perspective view of certain of the operating parts of the machine showing an outer wrapper about to be applied to a bundle of spaghetti sticks;

Fig. 6 is a view similar to Fig. 5 of the next successive stage in the operation of forming the package showing the bundle of spaghetti just after the initial phase of the wrapping operation;

Fig. 7 is a view similar to Fig. 6 showing a further stage of the wrapping operation;

30 Fig. 8 shows the wrapping operation completed except for the final folding-under of the ends of the wrapper and

Fig. 9 shows, in perspective, one end of a finished package looking from underneath the same.

40 Prior to the use and operation of the machine constituting the present invention, certain preliminary steps are carried out which comprise gathering a plurality of sticks of spaghetti of approximately equal lengths and piling them in parallel aligned relationship to provide a unit weight of predetermined amount, such as 12 oz. or 1 lb. The quantity of spaghetti which is desired to be included in a package is then encircled by a central band which is placed tightly therearound to form the sticks of spaghetti into a bundle of spaghetti 10. This central encircling band serves to minimize or reduce subsequent relative movement of the sticks 50 of spaghetti but cannot entirely eliminate the

same. It also acts to form a unit adapted for wrapping purposes. This central encircling band is preferably composed of a transparent material such as cellophane or waxed paper, the ends of which are suitably secured or sealed by a solvent or adhesive or by heat or in any other known or suitable manner. The bundle of spaghetti so produced is then inserted into a (cardboard) supporting and protective element 11 having upstanding ends 12. The bundle of spaghetti has one side resting on element 11, the ends 12 of which cover the ends of the bundle of spaghetti. The bundle of spaghetti and the element 11, sometimes called a cardboard boat, are fed to the machine in which the outer tightly-fitting wrapper of cellophane or waxed paper 13 is applied, as will be hereinafter more fully set forth. The initial gathering and weighing of the spaghetti sticks and the formation thereof into a bundle for subsequent wrapping purposes as well as the application of the outer wrapper can be carried out by hand. The construction of the finished package and the procedure for producing the same independently of any particular machine do not per se form part of this invention but constitute the subject-matter of copending application Serial Number 1,079, filed January 8, 1948, by A. Z. Vermylen for "Spaghetti Package and Method of Producing the Same."

In applying the cellophane or waxed paper outer wrapper 13 to the bundle of spaghetti consisting of a group of spaghetti sticks with the central encircling band, such bundles are successively fed as by a large grooved or slotted feeding drum or wheel (not shown) or by any other suitable means to the feed table 14 of the wrapping machine, which, in this case, is a standard "Oliver 799" cake wrapping machine which has been modified pursuant to the present invention. Such a bundle is indicated by the numeral 15 and is shown in Figs. 2 and 3, being moved by the spaced cross bars 16 of endless conveyor chains 17 onto the vertically movable platform 18 of the machine proper, the platform being at this time in its lowermost position. The end of the feeding table 14 is somewhat spaced from platform 18 and in the intervening space the sprocket wheels 19 are mounted on and turn with the horizontal shaft 20 which is turned by chains 17. The chains 17 pass over such sprocket wheels and over other sprocket wheels (not shown) to form an endless chain and are suitably driven at any desired or convenient point. Also mounted on shaft 20 are the smaller sprocket wheels 21. Sprocket chains 22 pass around sprocket wheels 21 and also around sprocket wheels 23, which are mounted on a shaft 24. Sprocket chains 22 carry fingers 25, as shown. It will be appreciated that, as the bundle of spaghetti to be wrapped comes to the end of feed table 14, one set of the fingers 25 propels the said bundle onto the platform 18 of the modified Oliver machine preparatory to applying the outer wrapper thereto, said fingers operating in slots 26 provided for that purpose in the feed table.

The platform 18 on which the bundle of spaghetti above referred to is received is mounted for vertical movement. This is accomplished by connecting platform 18 to a wrapper-receiving surface 27 by means of uprights 28. The wrapper-receiving surface 27 has depending plates or skirts 29 at its ends which are provided with trunnions 30 which are adapted to move up-

wardly and downwardly in the channel frames 31, such movements being imparted to members 29 by means of one or more links 32 eccentrically pivoted to said member. Appropriate upward and downward movements at predetermined intervals are imparted to surface 27 via link 32 from other moving parts of the machine which effect such movements in synchronism with the remaining machine movements to be described.

10 A guide plate 33 having an upturned lip 34 is mounted in vertical spaced relationship over surface 27 for a purpose which will be hereinafter explained.

15 The cellophane or waxed paper 13 which is to be used for wrapping purposes is fed into the machine as a continuous strip along the upper surface of the wrapper feed table 36, being moved along by the conveyor belt 35, which also serves to keep the wrapping material in flat, unwrinkled condition. At the inner end of table 36 is a block 37 which is secured in place in the position shown, spaced sufficiently above the end of table 36 to permit the wrapping material to pass between it and the table. The inner (right hand 20 in Figs. 2 and 3) vertical surface of block 37 is provided with the stationary member 38 of a cutting or shearing device, the movable portion 39 of which is secured to the bar 40 at the distal end of the rod 41, which is pivotally secured as at 25 42 to a stationary part of the machine framework, such as 43. Rod 41 has an arcuate depending arm 44 terminating in a journaled roller 45 which is adapted to follow the profile of the cam 46, which is rotatably mounted on a stub shaft 47. The profile of cam 46 is shown as being in the form of a smooth cylinder except that that at one point it has a protuberance 48 extending radially outwardly so as to form a means for raising the movable portion of the cutter into 30 cutting relationship with the stationary portion thereof to sever the sheet or strip of wrapping material when the cam protuberance 48 is in contact with the roller 45. Rod 41 is normally spring-urged into inoperative or non-cutting position by 35 means of a spring 49, one end of which is secured to the rod 50 and the other end of which is secured at 51 to a stationary part of the machine. The cutting and non-cutting positions of these members are clearly shown at the left central portions 30 of Figs. 2 and 3, respectively.

40 It will be noted from Fig. 2, in particular, that platform 18 and table 14 are in horizontal alignment when the platform is in its lowermost position. As the bundle of spaghetti in the cardboard boat 11 moves onto platform 18, under the impetus of fingers 25, said bundle of spaghetti pushes laterally against a severed sheet of wrapping material which has been cut off during the previous cycle of the machine and fed through 45 the throat between surface 27 and guide plate 33 to a holding mechanism, indicated as a whole by the numeral 52 (Figs. 5 and 6). From Fig. 5 it will be appreciated that one end of the severed sheet of wrapping material 13 is held in such 50 holding mechanism but that the other end thereof is still between surface 27 and guide plate 33 so that there is an intermediate portion of the wrapping material which extends vertically across the path of travel of the bundle of spaghetti. As 55 the bundle pushes against such intermediate portion in moving onto the platform 18, the wrapping material is bent around the bundle of spaghetti and, as the latter continues to move (to the left), it draws the lower end of the sheet of 60 wrapping material out of its previously recited 65 70 75

position between the surface 27 and the guide plate 33 and causes it to assume a predetermined position beneath the bundle of spaghetti when the latter has been moved completely onto the platform 18 as shown in Fig. 2. As it moves onto the platform 18 the bundle of spaghetti is engaged by the dog 53, which extends lengthwise of the platform and is slidably mounted thereon. The movement of the dog under the influence of the moving bundle of spaghetti is yieldingly resisted by the thickened ends 54 of the vertical bars 55 which are pivotally and hingedly mounted on the pintles 56 carried by the angle plates 57, the lower ends of which are suitably secured to said platform 18. The vertical bars 55 are constantly urged toward the incoming bundle of spaghetti by springs 58 helically surrounding cores 59, one end of each of which is secured to one of said plates 57. The tension of the springs is so adjusted as not to force the bundle back off the table once it has cleared the fingers 25, but is sufficient to insure that the dog 53 presses against the bundle with enough force to prevent the lower end of the wrapper from being drawn farther along between the dog and the bundle. In addition to its functions of holding the wrapper snugly against the side of the bundle and preventing further relative movement of the lower end of the wrapper with respect to the bundle once the bundle and the cardboard boat 11 have been positioned on the platform, the dog 53 also acts to bring about realignment of any of the spaghetti sticks that may have become turned slightly laterally with respect to the length of the bundle during the feeding of the bundle to the wrapping station. As the platform 18 moves upwardly, the remainder of the sheet is gradually bent around down over the upper surfaces of the bundle of spaghetti from the oblique position shown in Figs. 2 and 6 until the other end of the sheet of wrapping material is pushed under the cardboard boat and overlaps the end of the sheet which has already been placed thereunder as above explained.

In order to insure a snug and tight fit of the wrapping material around the bundle of spaghetti, one end of the sheet 13 is held in the holding device 52 previously referred to during the commencement of the wrapping operation and continuing substantially throughout the completion thereof. This holding mechanism includes a plate 60, a vertically movable link 61, a connecting link 62, a pivotally movable member 63 and spaced rollers 64 carried thereby. The plate 60 is secured to a stationary portion of the machine in horizontal alignment with the table 36 along which the wrapping material is fed prior to its severance into sheets and in horizontal alignment with the surface 27 when it is in its uppermost position. This relationship is clearly shown in Fig. 3. Consequently, it will be understood that each severed sheet of wrapping material is fed through the throat between surface 27 and guide plate 33 onto plate 60 and that at such time the holding mechanism is in inoperative position, as also shown in Fig. 3. Then, when severance of a particular sheet has been completed and surface 27 begins to move downwardly, the holding mechanism is caused to operate through the agency of the vertical link 61, the upper end of which has one end of connecting link 62 pivoted thereto. The other end of link 62 is rigidly connected to the pivoted member 63. When surface 27 begins to move downwardly, vertical link 61 is also caused to move downwardly, thus actuating the

linkage described to bring the rollers 64 (only one of the two rollers being visible in this figure) into the position shown in Fig. 2 in which they are in firm contact with the wrapping material adjacent the end thereof. The rollers 64 are preferably made of hard fiber or rubber surfaced. Thus the wrapping material is held with sufficient force to insure that the wrapping material does not slip or become slack but remains under sufficient tension to provide a smooth fit which tightly covers the bundle of spaghetti. As shown in Figs. 2, 5 and 6, the member 63, when in its lowered position, substantially fills the space between the plate 60 and an idle roller 70, to be further described. In this position the member 63 not only carries the rollers 64 into holding position with respect to the end of the wrapper, but also functions to prevent any of the spaghetti sticks from moving laterally into the space beneath the roller 70 and becoming broken or causing the wrapper to tear.

It will be appreciated that, as the bundle of spaghetti on its cardboard boat moves onto platform 18 against dog 53, end tuckers form a lateral fold 65 at each end of the bundle of spaghetti, as will be clearly understood from Figs. 6 and 8. Each such tucker comprises a horizontal guide bar 66 held at one end in a slotted support 67 which is suitably secured to the platform 18. It will be clearly appreciated that as the bundle of spaghetti moves against dog 53 each of the guide bars 66 causes the wrapping material to be bent over and held down to constitute a fold, the exact nature of which is illustrated in Fig. 8, for example. After this is accomplished, the platform 18 moves upwardly and, as it does so, the sheet of wrapping material becomes wrapped around the upper (convex) surfaces of the bundle of spaghetti, the weight of the bundle of spaghetti and the pressure of the dog 53 being adequate to prevent the end of the sheet already thereunder from becoming displaced. This action continues as the platform 18 moves upwardly until ultimately the uppermost position is reached, as shown in Fig. 3, at which time the upper surface of the package is brought into contact with a pair of inverted U-shaped holders 68 which are carried by depending arms 80 of yoke 80'. The holders 68 take control of further movement of the package and maintain the wrapping material held down in its snugly fitting position about the bundle of spaghetti sticks.

Due to a reciprocating carriage mechanism to be hereinafter described, the partially wrapped package of spaghetti now begins to move from left to right and the dog 53 becomes a follower, sliding along under the influence of bracket plates 55, as the incompletely wrapped package of spaghetti is gradually propelled over onto the plated 69, which is mounted on a stationary part of the machine above previously recited plate 60. It will be further noted that an idle roller 70, having intermediate raised friction bands or surfaces 70', is journaled to the machine frame 90 adjacent one end of plate 69 and that one end of a bell crank lever 71 pivoted at 72 is positioned adjacent the idle roller 70. The other end of the bell crank lever 71, which is substantially in the form of a right angle, is connected to the upper end of the long vertical link 73, the other end of which is suitably actuated by a moving part of the machine, as will be understood, and the timed relationship of the actuation of said long vertical link 73 is such that, as the incompletely wrapped package moves onto plate

69, the projecting end of bell crank lever 71 moves in a counterclockwise direction until it contacts idle roller 70, thus preventing the same from rotating. Consequently, the end of the sheet of wrapping material is frictionally held or its movement is retarded during a part of the left-to-right movement of the incompletely wrapped package sufficient to maintain the wrapping sheet in snug and tight relationship with the spaghetti and until said end of the sheet is brought beneath the cardboard boat 11 in overlapping relationship with the other end of the wrapping material which is already in place, as previously described. The idle roller 70 is promptly thereafter released so that it can turn and act as a support for the package as the latter continues to move over the space between platform 18 and plate 69. As the now enclosed bundle of spaghetti moves from left to right (Figs. 2 and 3), a pair of tuckers 74 forms another fold 75 similar to the one 65 originally made but in the opposite direction, so that the ends of the package appear as shown in Fig. 8. The mechanism, to be further described, controlling the movement of the inverted U-shaped holders 68 now causes them and the wrapped package of spaghetti to continue to move toward and eventually into the heating or sealing unit designated as a whole by the numeral 76. As the package is moved toward unit 76, a pair of spring metal guides 77 located adjacent unit 76 ride up over the horizontal projecting folded ends of the wrapping material (see Fig. 8), deflect the same downwardly and bend them up under the ends of the package, as will be clearly seen in Fig. 9. The wrapping of the package is now complete and the sticks of spaghetti are maintained in an immobilized condition. The package then passes on into the unit 76, which is provided with any suitable sealing or heating means, such as steam pipes or electrical heating coils when heat sealing is to be effected, so that the ends of the wrapping material are heat-sealed or otherwise secured in the position shown in Fig. 9. As more particularly described hereinafter, the inverted U-shaped holders 68 are tripped and disengage themselves from the package, following which they are returned to their initial position ready for another cycle. The package is caused to move out of the heater and onto a discharge conveyor 78 under the influence of the pushers 92 simultaneously with the next forward movement of the holders 68. The discharge conveyor 78 carries the successive completed packages to a suitable point of discharge.

The inverted U-shaped holders 68 are integral or unitary with the depending arms 80 of the yoke 80'. The yoke 80' is supported adjacent its mid-portion by the distal ends of the pair of arms 81 that are respectively mounted for pivotal movement about the pintles 82 carried on the opposite sides of the tubular sleeve 84 which reciprocates along the bar 83. Also connected to the distal ends of the pivoted arms 81 is the tripping device 79, which extends first horizontally from its connection with arms 81 and then upwardly at a relatively small angle to the horizontal.

Sleeve 84 is provided with two upstanding brackets 85, the lower flanged ends of which are secured to said sleeve. These brackets establish a connection with a carriage which includes a pair of trapezoidally shaped end frames 86 connected together by rods 86' and 86''. These rods are positioned between the brackets 85 so that,

under the influence of the reciprocating chain 87, which is connected to the lower end of the carriage, the entire carriage reciprocates between the full and dotted line positions shown in Fig. 3. The lower end of the carriage is provided with stub shafts 88 carrying rollers 88' which reciprocate within the fixed guide rails 89 attached to the side frames 90 or other suitable stationary supporting members. A pair of longitudinally extending bars 91 terminating in the downwardly extending pushers 92 are supported intermediate the end frames 86 of the carriage and the central bar 83. The pushers 92 are pivoted at 92' to the bars 91 so that they may be rotated in a counterclockwise direction only, as viewed in Figs. 2 and 3, thus permitting them to pass over a package positioned at the heating station as they are returned to initial position with the carriage.

As the carriage moves from left to right (Fig. 3), carrying with it the yoke 80' and the holders 68, the pushers 92 are likewise advanced and serve to propel the package previously deposited at the sealing station 76 onto the discharge conveyor 78 at the same time as the next package is brought to the sealing station 76 by the holders 68. When the carriage has travelled a sufficient distance to bring such next package to the sealing station 76 and the previous package has been transferred to the conveyor 78, the pivoted arms 81, carrying the yoke 80' and the holders 68, are moved upwardly about their pivot points on the sleeve 84 sufficiently to insure that they will clear the package then positioned at the sealing station 76 on the movement of the carriage. This pivoting movement is brought about by means of a roller 93 supported on the arm 94 connected to the rotatable shaft 95. The shaft 95 carries a sprocket wheel 96 actuated by sprocket chain 97 and the construction and arrangement of these parts are such that the arm 94 carrying the roller 93 continuously rotates with the shaft 95 in a clockwise direction. Thus as shown in Fig. 3 in relationship to the dotted line representation of the sliding sleeve and package holding assembly, the arm 94 rotates in a clockwise direction in timed relation to the movements of the carriage, thus bringing the roller 93 beneath the tripping finger 79 and, as the arm 94 continues to rotate, the roller lifts the yoke 80' and the associated holders 68 while pivoting the supporting arms 81 about their pivot points 82. When the package holding and ejecting assembly has moved back sufficiently toward its full line position of Fig. 3 to clear the package positioned at the sealing station, the roller becomes disengaged thus permitting the inverted U-shaped holders to drop down into their full line position ready to engage the next package and to repeat the cycle just described seriatim. As previously indicated, the one-way pivoted connection of the pushers 92 to the arms 91 permits these pushers, in the return movement, to pivot and pass over the package 15 that has just been brought to the heating station.

It has not been deemed necessary to illustrate or describe the remaining parts of the machine since they are the usual parts found in a machine of the type above referred to and are per se known and do not form a part of this invention. The invention rather comprises aforementioned modifications of, and additions to, an "Oliver 799" cake wrapping machine or any of various other known forms or types of wrapping machine adapted to form a basis for the present invention. It is to be understood, however, that the modifications and additions to any such machine,

which are herein described and claimed, are presented as exemplary of the invention and not as limitative, since within the scope of the invention various changes may be made without departing from the spirit or principles hereof. The invention is rather that defined by the appended claims.

The term "spaghetti," as employed in this application, covers other edible and inedible materials having the form or shape of sticks of spaghetti and is to be so understood.

I claim:

1. In a machine for wrapping bundles of banded spaghetti, a platform for supporting a bundle of spaghetti to be wrapped, means for reciprocating said platform vertically between a loading position to an unloading position, means for supplying wrappers, means cooperating with said platform and operating in timed relation with the movements thereof to apply one of said wrappers around said bundle, said wrapping means including means for imposing tension on said wrapper to bring said wrapper into snugly fitting relation with said bundle, a holder having a lower surface conforming to the upper and lateral surfaces of said bundle means including a pivotable arm for supporting said holder and positioning the same at the unloading position of said platform, said holder being adapted to hold the wrapper in closely fitting engagement with said bundle when the platform has been brought into its unloading position, means for reciprocating said holder horizontally between the unloading position of said platform and a sealing station, and means cooperating with said holder-supporting means for pivoting said holder upwardly away from contact with said bundle when the bundle has been brought to the sealing station and for maintenance of said holder in such raised position until the holder has been returned toward said unloading station.

2. In a machine for wrapping bundles of banded spaghetti, a platform for supporting a bundle of spaghetti to be wrapped, means for moving said platform vertically from a loading position to an unloading position, means for supplying wrappers, means cooperating with said platform and operating in timed relation with the movements thereof to apply one of said wrappers around said bundle, said wrapping means including means for imposing tension on said wrapper to bring said wrapper into snugly fitting relation with said bundle, an inverted U-shaped holder, means for supporting said holder and positioning the same at the unloading position of said platform, said holder being adapted to hold the wrapper in closely fitting engagement with said bundle when the platform has been brought into its unloading position, means for moving said holder horizontally between the unloading position of said platform and a sealing station, means including a pusher arm disposed in advance of said holder and movable horizontally in synchronism therewith for moving a package

of spaghetti previously deposited at said sealing station away from said station as the next package is brought thereto by said holder, and means cooperating with said holder for moving said holder out of line with the package positioned at said sealing station and to maintain said holder in raised position until it has cleared said sealing station in its return movement and a one way hinge support for said pusher arm to permit it to pass over a package at the sealing station during its return movement.

3. In a machine for wrapping bundles of banded spaghetti, a platform for supporting a bundle of spaghetti to be wrapped, means for moving said platform vertically from a loading position to an unloading position, means for supplying sheets of wrapping material, means cooperating with said platform and operating in timed relation with the movements thereof to apply one of said sheets around said bundle, said wrapping means including a first stationary horizontal plate mounted above said loading position and adjacent the path of movement of the platform between said loading and unloading positions and a second stationary horizontal plate mounted above said first stationary plate, a bar of substantial width, means supporting said bar for pivotal movement about an axis extending longitudinally of the bar adjacent one edge thereof and parallel to and between said plates and spaced from said first plate, rollers carried by said bar at the edge thereof opposite said axis, and means for rotating said bar about said axis between a first substantially vertical position in which said rollers cooperate with said first plate to grip said wrapping material for tensioning the same and in which said bar backs up the sheet of wrapping material being applied to the bundle to prevent puncture of said sheet by a stick of spaghetti projecting toward said space, and a second position in which said rollers release said material.
